UNITED STATES PATENT OFFICE.

ARPAD BARENYI, OF BERLIN-LICHTERFELDE, GERMANY.

STARTER FOR INTERNAL-COMBUSTION ENGINES.

Application filed January 13, 1923. Serial No. 612,544.

To all whom it may concern:

Be it known that I, ARPAD BARENYI, a citizen of Germany, residing at Berlin-Lichterfelde, in the State of Prussia, Germany, 5 have invented certain new and useful Improvements in Starters for Internal-Combustion Engines; and I do hereby declare the following to be a full, clear, and exact description of the invention, such as will 10 enable others skilled in the art to which it appertains to make and use the same.

My invention relates to improvements in starters for internal combustion engines, and more particularly in starters of the type in 15 which the motor for starting the engine is disposed coaxially of the crank shaft of the engine, and in which in addition a hand operated crank is provided for starting the engine by hand when there is need or desire 20 so to do. One of the objects of the improvements is to provide a starter of this type in which the gearing interposed between the motor and the crank shaft of the engine is disposed coaxially of the said crank shaft 25 and motor. With this object in view I provide a transmission gearing in which the operative parts are disposed concentrically to the axis of the gearing, and I mount the said gearing so that the concentric axis is in 30 alignment with the axis of the crank shaft and the motor. Another object of the improvements is to provide a system, in which the starting motor and the transmission gearing are disposed within a cylindrical 35 casing by means of which the starter and its gearing may be mounted on or dismounted from the engine as a unit. Another object of the improvements is to provide a system in which the hand operated crank is adapted 40 to operate the crank shaft of the engine through the intermediary of the shaft of the motor, and in which means controlled by the said crank are provided for throwing 45 the transmission gearing out of operation as gearing and for connecting the said motor shaft to rotate as a unit with the crank shaft of the engine. With these and other objects in view my invention consists in the matters to be described hereinafter and particularly 50 pointed out in the appended claims.

For the purpose of explaining the invention two examples embodying the same have been shown in the accompanying drawings in which the same reference characters have

been used in all the views to indicate corresponding parts. In said drawings,—

Fig. 1, is an elevation showing the engine and the starter in a general way, in assembly with the engine,

Fig. 2, is a vertical longitudinal section 60 drawn to larger scale of the starter with its transmission gearing,

Fig. 3, is a cross-section taken on the line 4—4 of Fig. 2,

Fig. 4, is a cross-section taken on the line 5—5 of Fig. 2,

Fig. 5 is a cross-section taken on the line 6—6 of Fig. 2,

Fig. 6, is a partial development in a single plane of certain annularly arranged apparatus shown in Fig. 5,

Fig. 7, is a detail view showing in side elevation the hand operated crank and the cap of the armature shaft cooperating therewith,

Fig. 8, is a partial section corresponding 75 to Fig. 3 and showing a modification, and

Fig. 9 is a diagrammatic view illustrating a detail in the structure as shown in Fig. 8.

In describing the invention reference will be made to an electric starter, and more particularly to a starter which is adapted when the engine is running to serve as a generator and to supply electric current to a storage battery or other current consumer. The type of the motor-dynamo provided in the system shown in the figures has been shown and described in the application for patent of Barenyi and Kaemmerer, Ser. No. 603,764, filed in the Patent Office of the United States on November 28, 1922. As my invention does not relate to the specific type of the motor-dynamo I shall not describe the same in detail, short reference to the main parts of the motor being sufficient to give a clear understanding to those skilled in the art.

In the example shown in Figs. 1 to 7, my improved system comprises an internal combustion engine 1 connected by a clutch 2 of any known or preferred form with a starter 100 3. The starter comprises a cylindrical casting 5 enclosing the operative parts. In anti-friction bearings 6 and 7 provided respectively in the end wall 8 and a supporting member 9 located internally of the casting 5 a motor shaft 10 is mounted to which the armature 11 of a motor-dynamo is keyed. The field poles 12 of the motor-dynamo are 105

secured to the casing 5 by screws 13, and they carry field exciting coils 14. At the left of the armature a commutator 15 is secured to the shaft 10, and the windings of the armature are connected with one of their ends directly to the lamellæ of the commutator 15, and the opposite ends of the coils are passed through bores of a ring 16 carrying the lamellæ, and they are secured to a ring 17 adapted to be rotated relatively to the commutator. The range of rotation of ring 17 relatively to commutator 15 is limited and defined by means of a transverse pin 48', which, integrated with the ring 17, extends diametrically across the ring and through circumferentially extending slots in shaft 10. By such means the armature coils may be shifted and connected in alternate arrangement, for operation alternately as a generator, or as a motor, as has been described in the aforesaid application of Barenyi and Kaemmerer. The transverse pin 48' extends diametrically through a rod 43, concentrically arranged within and movable both rotatably and telescopically within the hollow shaft 10, and the slots in shaft 10 through which the pin 48' extends, permit of movement of the pin 48' and with it of ring 17 in axial direction also, through a limited range, relatively to shaft 10. This for purposes presently to be indicated.

In the example shown in Fig. 2 the transmission gearing is in the form of a planetary gearing comprising a drum 18 having its hub 19 mounted on an anti-friction bearing 20 the outer race way of which is provided by the annular member 9. The said drum is formed with internal teeth 21 engaging in the teeth of two sets of planet gear wheels 22 and 23, the gear wheels 22 being mounted on stub shafts 24 provided on a disk 25 rotatable on the reduced end of the shaft 10. The shaft 10 is formed with gear teeth 60 meshing with the gear wheel 22, and the hub 45 of the disk 25 is formed with gear teeth 62 meshing with the gear wheels 23. The gear wheels 23 are mounted on stub shafts 27 provided on a disk 28 made integral with a stub shaft 29 having one of the members of the clutch 2 secured thereto. As shown the disk 28 is guided within the drum 18 through the intermediary of an anti-friction bearing 30, and the stub shaft 29 is mounted in an anti-friction bearing 31 provided in the left hand end wall 32 of the casing 5.

Near the left hand end the shaft 10 carries, with capacity for longitudinal or telescopic movement upon it, an annular coupling member 33 formed with cut-out portions 34 providing chambers and cam ways 35 for rollers 36 having their axes guided in slots 37 made in the body of the member 33 and in a ring 38 secured thereto, and being acted upon by springs 39. The rollers 36 bear on the cam faces 35 and the inner wall

of the hub 19, and when turning the shaft 10 in anti-clockwise direction in Fig. 3, which direction of rotation corresponds to the starting of the engine by the motor, the rollers 36 engage in the broad ends of the chamber 34, so that the annular member 33 rotates independently of the drum 18. If however the drum 18 is rotated by the engine in anti-clockwise direction, the rollers engage in the narrow parts of the chambers 75 34, so that they are clamped between the cam ways 35 and the inner wall of the hub 19 and couple the drum 18 with the shaft 10. The shaft 10 is then powerfully driven and the motor-dynamo then serves in its capacity as a dynamo and generates current for charging a storage battery or for other purpose. The drum 18 is provided with circumferential teeth 59 (cf. Fig. 4) cooperating with a tooth 58 of a spring pressed 85 plunger 57 borne in the wall of casing 5 and adapted to lock the drum in position. The teeth 59 are beveled at one side, so that they are adapted when moved in one direction to push the plunger out of locking engagement. In opposite direction the engagement is secure. Therefore, the drum is locked by the plunger as against rotation in one direction, and it is free to rotate in the opposite direction. 95

The annular member 33 is formed with a flange 40 formed with coupling members 41 located in position for cooperation with complementary coupling members 42 formed on the hub 19. The annular member 33 is adapted to be shifted longitudinally of the shaft 10 for throwing the claws 41 and 42 into or out of coupling engagement. In the example shown in Figs. 2 and 3 the means for shifting the member 33 consist of the rod 43 already mentioned, this rod, in addition to being rotatable, is longitudinally shiftable within the axial bore 44 of the shaft 10, and it carries a second transverse pin 45 which passes through slots 65 of the shaft 10 and engages in transverse bores of the member 33. At its right hand end projecting beyond a cap 4 secured to the shaft 10 the rod 43 has a head 46 secured thereto, and within an enlarged portion 47 of the axial bore of the shaft 10 a spring 48 is located, which bears respectively on an annular shoulder provided at the left hand end of the bore 47 and on the head 46, which spring 110 has the tendency to push the rod 43 to the right and into the position shown in Fig. 3 in which the coupling members 41 and 42 are out of engagement and the head 46 projects beyond the cap 4. 115

As has been explained above, the plunger 57 is adapted to be thrown out of locking engagement with the teeth 59 by the beveled rear faces of the said teeth. In order to avoid the noise consequent upon the tooth 58 sliding over the teeth 59 I prefer to pro- 120 125 130

vide automatic means to operate at suitable time and lock the said plunger in non-locking position. As shown (Figs. 2, 5, and 6) the member 9 is constructed to provide an 5 annular housing, and within the said housing a segmental slide or carriage is movable circumferentially of the casing 5. As shown the said carriage consists of a pair of spaced segmental plates 100 mounted on three rollers 101 guided between the inner wall of 10 casing 5 and member 9. One of the said plates is secured to a disk 102, and the other one carries a locking member 103 projecting laterally therefrom and into position for 15 locking engagement with the plunger 57, as is shown in Fig. 4, said plunger being formed with a shoulder 104 for arresting the circumferential movement of the member 103 and the carriage. A spring 105 is attached with one end to the carriage and with its opposite end to an eye 106 secured to the member 9, which spring tends to pull the carriage with the arm 103 into locking engagement with the plunger 57. To the member 20 9 an electromagnet 107 is secured the armature 108 of which is rockingly mounted on the said member at 109 and connected by a link 110 with the carriage. The electromagnet is connected by leads 111 with a 25 source of electric energy, preferably the battery connected with the motor-dynamo, and a switch adapted to be closed when connecting the motor-dynamo for operating as a motor, for retracting the locking member 30 103 away from the plunger 57 and permitting the tooth to come into locking engagement with the claws 59.

The leads 111 are passed into the casing 5 through a tubular member 112. Through 35 40 the same member leads are passed from the battery to the brushes of the armature. The stub shaft 29 is formed with teeth 50 engaging a spur wheel 51 for operating a distributor enclosed within a casing 52 mounted on the casing 5. As the distributor 45 does not form a part of the invention I deem it not necessary to describe the same.

The cap 4 is provided with a flange 53 (cf. Fig. 7) carrying undercut teeth 54 adapted for engagement by a crank 55 formed with corresponding undercut teeth 56 and adapted for engagement with the head 46 for pushing the rod 43 inwardly 50 against the action of the spring 48.

The operation of the apparatus is as follows: When starting the engine by the motor-dynamo acting as a motor the electromagnet 107 is energized for retracting the locking member 103 away from the plunger 57, and the drum 18 is locked in position by the teeth 58 of the plunger 57 engaging in the teeth 59 of the drum. The rod 43 is 55 free of restraint such as may be exerted through crank 55, but responsive to the tension of spring 48, stands, as seen in Fig. 2, at the right-hand end of its range of longitudinal traverse. The parts named being in the positions indicated, circuit is closed from the battery through the armature windings and the armature is powerfully rotated. The ring 17 lags and the pin 48' comes to its extreme rearward position with respect to the direction of the rotation so established, and in that position the arrangement of the connections for the armature windings is that suited to the character of motor, which the apparatus now assumes, —all as explained in the Barenyi and Kaemmerer application alluded to. While the apparatus is so operating in its capacity as a 70 motor, the mechanically rotated shaft 10 makes connection with the planetary gearing and thence with shaft 63, only through the teeth 60. These impart rotary movement to the planet gear wheels 22 carried by the disk 25. As the drum 18 is at this time locked in position the said gear wheels 22 revolve within drum 18 and thus impart rotary movement at diminished speed to the disk 25. The teeth 62 formed on the hub 80 of the said disk impart rotary movement to the gear wheels 23, which by reason of their engagement with the teeth 21 of the immovable drum 18, revolve as they rotate and carry along the shafts 27 on which they are mounted. Thus they impart rotary movement at a speed still further diminished to the disk 28 and to the stub shaft 29. The rotary movement of the shaft 29 is transmitted to the crank shaft 63 of the engine. 85

After the engine started by the movements just described, has become self-operating it builds up speed and automatically connects the motor-dynamo for operating as a generator, as has been described in the aforesaid application of Barenyi and Kaemmerer. When the engine is in operation the velocity of the drum 18 exceeds that of the annular member 33. The tooth 58 of the plunger 57 is thrown out of locking engagement with the teeth 59 by reason of the beveled rear faces of said teeth, and the rollers 36 are moved by the hub 19 of the drum 18 into the narrow portions of the chambers 34. Thereby the hub 19 and the member 33 are coupled to each other. Now the rotary movement of the crank shaft 63 is directly transmitted through the disk 28 and the gear wheels 23, 22, the drum 18 and the member 33 to the shaft 10, at undiminished speed, the ratio of transmission being 1:1. The current supply to the electromagnet 107 is interrupted by hand or automatically, so that the spring 105 shifts the carriage 100, 101 with the locking member 103 in position for locking the plunger 57 in retracted position. 100

If it is desired to start the engine by hand, the crank 55 is placed on the cap 4 with its teeth 56 engaging the teeth 54. The under- 105 110 115 120 125 130

cut faces of the teeth pull the crank inwardly and against the head 46, so that the rod 43 is shifted to the left and the armature windings are retracted from the lamellae 15 by the rod 48. Furthermore, the interlocking members 41 and 42 are thrown into engagement with each other by the rod 45, so that the drum 18 is directly coupled through the member 23 with the shaft 10. Therefore the operation of the crank 55 is directly transmitted to the crank shaft 63, the planet gearing serving merely as keys, uniting shaft 10 and drum 18 with disk 28. As soon as manual cranking ceases, spring 48 carries rod 43 and with it ring 17 in axial direction back to original position.

In Figs. 8 and 9 I have shown a modification in which another transmission gearing is provided between the motor-dynamo 20 and the crank shaft. As shown the stub shaft 70 is formed with a spherical head 71 on which a disk 72 has universal movement. The disk 72 is provided with an axial arm 73 having a spherical head 74 engaging in an eccentric socket 75 of the rear end of the armature shaft 76, an anti-friction bearing 77 being preferably interposed between the head 74 and the wall of the socket 75. The driving shaft 76 is rotatably mounted 30 through the intermediary of an anti-friction bearing 78 within a rotary drum 79 mounted in an anti-friction bearing 80 provided internally of the cylindrical casing 81. At the side of the driving shaft 76 the disk 72 is provided with teeth 82 cooperating with teeth 83 formed on the drum 79, the teeth 82 and 83 providing meshing bevel gear wheels. The gear wheel 83 is perpendicular to the axis of the shafts 70 and 76, and the 40 points of the cones of the bevel gear wheels 82 and 83 coincide with the center $\bigcirc$ of the spherical head 71 and therefore with the center of the universal movement of the disk 72. The inclination of the gear wheel 82 depends on the eccentricity of the socket 75.

The drum 79 is formed with circumferential teeth 84 beveled at one side and corresponding to the teeth 59 of the drum 18 shown in Fig. 2, and adapted to be engaged 50 by a spring pressed locking member 84' adapted to lock the drum as against rotation in a direction opposite to the starting movement and permitting rotation of the drum in the direction for starting the engine, as has been described with reference to Figs. 2 and 3. Also in this case electro-magnetic locking means are provided for locking the member 84' in retracted position when operating the system as a generator, the construction being similar to the one described with reference to Figs. 2 to 6, so that it is not necessary to repeat the description.

The disk 72 and the shaft 70 are formed 65 respectively with flanges 85 and 86, the

flange 85 embracing the bevel gear wheel 82. The said flanges are formed with bevel gears 87 and 88 meshing with each other at a point opposite to the point where the bevel gear wheels 82 and 83 are in engagement 70 with each other.

The numbers of the teeth 82 and 83 are different, while the numbers of the teeth 87 and 88 are alike. Therefore, in order to insure correct engagement of the teeth 87 and 88 care must be taken that the diameters and the pitch of the said gears correspond to each other. For this reason the gears are disposed so that the point where the pitch lines are in contact with each other is within a plane passing through the center $\bigcirc$ of the head 71 and dividing the angle α of the inclination of the disk 72 relatively to the plane perpendicular to the axis of the shafts 70 and 76 into equal parts, so that the angle of the said plane and a plane passing through the center $\bigcirc$ and perpendicular to the axis of the shafts 70 and 76 is equal to $\frac{1}{2} \alpha$. 85

The drum 79 is formed with clutch members 90 cooperating with clutch members 91 formed on a coupling sleeve 92 non-rotatable but axially slideable on the shaft 76 and engaged by a transverse pin 93 passing through slots 94 made in the hollow shaft 95 76 and secured to a rod 95 corresponding to the rod 43 shown in Fig. 2. By shifting the sleeve 92 to the left and bringing its clutch members 91 into engagement with the clutch members 90 the drum 79 is locked 100 relatively to the shaft 76, the construction being similar to that described with reference to Fig. 2.

The operation of the mechanism is as follows: When starting the engine by means of the electromotor the clutch member 92 is retracted from the position shown in Fig. 8, and the spring pressed locking member 84' engages the teeth 84 and locks the drum 79 as against rotation by the armature shaft 76. 105

The rotation of the shaft 76 is transmitted to the head 74 and the disk 72, the axis of the arm 73 moving along the surface of a cone having its points coinciding with the center $\bigcirc$. Therefore the bevel gear wheel 82 rolls on the bevel gear wheel 83 of the drum 79. It will be understood, that such rolling movement of the bevel gear wheel 82 would not result in a rotary movement 110 of the disk 72, if the number of the teeth of the gear wheels 82 and 83 were alike. But by providing the gear wheel 82 with a larger number of teeth as compared to the number of the teeth of the gear wheel 83 the disk 72 is rotated relatively to the drum 79, the direction of rotation being the same as that of the armature shaft. The drum 79 is locked in position by the member 84', and it takes up the reaction of the teeth 82 115 on the teeth 83. The rotary movement of 120

75

80

85

100

105

110

115

120

125

130

the disk 72 is transmitted through the gear teeth 87 and 88 to the flange 86 and the shaft 70 connected with the crank shaft of the engine. As the numbers of the gear teeth 87 and 88 are alike the number of revolutions of the shaft 70 is the same as that of the disk 72, and necessarily less than the number of revolutions of the shaft 76.

When it is desired to start the engine by hand the clutch member 92 is shifted to the left by means of a hand crank acting on the rod 95 in the manner described with reference to Fig. 2, so that the drum 79 is coupled to the shaft 76. Now the shaft 76, the drum 79, the disk 72 and the flange 86 move in unison, and the disk 72 does not perform rocking movement on the head 71. The locking member 84' is pushed out of engagement with the teeth 84, as has been described above with reference to Fig. 3. Therefore the whole transmission gearing is locked, and the power is directly transmitted from the shaft 76 to the crank shaft of the engine.

After the engine has built up speed, the velocity of the shaft 70 exceeds that of the shaft 76. If the engine has been started by the motor, the clutch members 91 of the member 92 are already out of engagement with the clutch members 90. The movement of the shaft 70 and the disk 72 is transmitted to the drum 79 transmitting the same to the shaft 76 through the spring-pressed clutch 96, 97, minutely illustrated in diagrammatic form in Fig. 9 at the ratio of one to one. It will be understood that the plunger 84' is provided with electromagnetic locking means of the construction described with reference to Figs. 1 to 7. The clutch 96, 97 is non-operative when starting the engine from the shaft 76, the teeth 96 riding on the teeth 97 by reason of their beveled rear faces.

While in describing the invention reference has been made to particular examples embodying the same I wish it to be understood that my invention is not limited to the constructions shown in the drawings, and that various changes may be made in the general arrangement of the apparatus and the construction of its parts without departing from the invention.

I claim:

1. In an internal-combustion engine, and in combination with an engine shaft, a motor-dynamo having an extensible and retractable two-part shaft, one of said shaft-parts carrying the armature of the motor-

dynamo, the other shaft-part carrying a make-and-break device for the armature windings, means for effecting relative shifting of the shaft parts, and power-transmission means connecting the dynamo-motor shaft with the engine shaft and adapted to transmit rotation of the extended motor-dynamo shaft to the engine shaft at undiminished speed, to transmit rotation of the retracted motor-dynamo shaft to the engine shaft at diminished speed, and to transmit rotation of the engine shaft to the motor-dynamo shaft at undiminished speed.

2. In an internal-combustion engine, and in combination with an engine shaft, a motor-dynamo having an extensible and retractable two-part shaft, one of said shaft-parts carrying the armature of the motor-dynamo, the other shaft-part carrying a make-and-break device for the armature windings, yielding means tending to maintain the shaft in retracted condition, manually operable means for extending the shaft against the tension of the means last named and for rotating the shaft, and power-transmission means connecting dynamo-motor shaft with engine shaft and adapted to transmit manual rotation of the extended motor-dynamo shaft at undiminished speed to the engine shaft, to transmit rotation under electrical power of the retracted motor-dynamo shaft at diminished speed to the engine shaft, and to transmit rotation of the engine shaft at undiminished speed to the motor-dynamo shaft.

3. In an internal-combustion engine, and in combination with an engine shaft, a motor-dynamo having a telescopically extensible and retractable armature shaft and a make-and-break device for its armature coils operated by telescopic movement of said shaft, power-transmission mechanism connecting armature shaft and engine shaft and adapted to transmit rotation at undiminished speed from the extended armature shaft to the engine shaft, to transmit rotation at diminished speed from the retracted armature shaft to the engine shaft, and to transmit rotation at undiminished speed from the engine shaft to the armature shaft.

In testimony whereof I hereunto affix my signature in the presence of two witnesses.

ARPAD BARENYI.
